PIT PROP

Walter Sylvester, Tunstall, England

Application January 12, 1933, Serial No. 651,343
In Great Britain January 23, 1932

14 Claims. (Cl. 254—104)

This invention relates to pit props and more particularly to wedge-type pit props which comprise a casing mounted on the end of the prop and a wedge mounted in the casing engaging 5 the end of the prop and the casing or a head piece, and arranged for driving in to fix or tighten the prop after it has been set in place.

Wedge-type pit props, while they are simple in construction and in practice the easiest props 10 to fix, have the serious disadvantage that considerable risks have to be taken in removing them. A prop of this kind is removed by driving out the wedge with a sledge hammer and at the last the release is sudden and may be followed 15 by such a sudden and heavy fall of the roof as to endanger the safety of the person removing it.

The object of the invention is an improved wedge-type pit prop not having the above disadvantages.

According to the invention, the pit prop is characterized in that the casing, which locates the wedge on the prop, is formed with an open front or side so that the prop may be withdrawn 25 laterally from under the wedge.

In the accompanying drawings:—

Fig. 1 is a side elevation of one example of pit prop made in accordance with the invention.

Fig. 2 is a front elevation of the prop shown 30 in Fig. 1.

Fig. 3 is a side elevation showing the relation of the parts during removal of the prop.

Figs. 4 and 5 are side and front elevations of a modified form of the invention.

35 Figs. 6 and 7 are side and front elevations of another modified form of the invention.

Figs. 8 and 9 are side and front elevations of a further modified form of the invention.

Figs. 10 and 11 are side and front elevations 40 of a modified construction of casing incorporating the head piece.

As illustrated in Figs. 1 to 3, the girder prop 12 having flanges 13 is fitted with an inclined cap 14. On the longer flange near the cap 14 are secured two lugs 15 having elongated slots 16, reinforcing pieces 17 being provided behind those parts of the flange. To these lugs is pivoted a member constituting a combined locking lever and link for drawing the prop, the member consisting of two locking levers 18, connected by a U-shaped bridge 19, and being attached by means of a pivot bolt 20 positioned at the junction of the levers and bridge piece and passing through and adapted to move freely 55 in the slots 16 of the lugs 15 on the prop. Each lever 18 has at its end an inwardly directed lug 21 having an arcuate face directed towards the pivot. The bolt 20 is secured by a pin 22 and washer 23.

60 On the end of the prop is also arranged a

casing 24 having a socket-like upper end to receive and locate a head piece 25. Below the socket, which may be rectangular or round, the casing is in shape three sides of a rectangle of a size adapted to fit over the end of the prop. 65 In one or both of the wings or sides of this lower part is a stud 26 which by engagement with the cap 14 or flanges 13 prevents the casing from leaving the prop. Within this lower part of the casing is also slidably arranged a 70 wedge 27 passing through a slot 28 in the rear wall of the casing and located by a bolt 29 in the sides, the end of which bolt engages in a groove 30 in the side of the wedge. On the sides of the lower part of the casing are formed 75 lugs 31 having arcuate faces to be engaged by the arcuate faces 21 of the levers 18, the ends 32 of the faces of the lugs 31 being rounded off to give a lead. The sides of the casing are also extended and formed with a notch 33 adapted 80 to engage a hub-part 34 provided at each lever around the pivot bolt.

For withdrawing the prop a chain link 35 is provided on the member 19 to which the chain of the drawing machine may be connected. 85 This link 35 has a locking pin 36 attached to it by a short chain 37, the locking pin being adapted to be inserted in a hole in one side of the casing 24 under the lug 21 to prevent the releasing movement of the lever 18. The chain 37 is purposely made short so that the pin requires to be withdrawn before the chain of the drawing machine can be attached to the link 35. 90

The casing may be made from sheet metal by folding and the sides may be made with a corrugation on either side, in which the wedge may be located and guided by a flange along its upper edge, suitable stops being provided to retain the wedge. Preferably also the engaging faces of the prop cap and wedge will be smooth and 95 of hardened steel.

In use, the prop is quickly fitted. Firstly, if not already so positioned, the casing is brought to the cap end of the prop and the levers moved into the position shown in Fig. 1 locking the casing on to the end of the prop. The wedge 27 is then drawn out to its extreme position and the prop with its head piece is placed in position, with a lid if necessary, in the usual manner and the prop finally secured by driving in the wedge. 105

To remove the prop, the chain of any type of drawing machine is attached to the link 35, the pin 36 being previously withdrawn to facilitate such attachment. As a pull is applied, the U-shaped bridge piece or link 19 lifts into the 110 horizontal position and with such movement it brings the levers 21 out of engagement with the lugs 18. Further pulling on the bridge piece or link is now only communicated to the upper end of the prop itself, which being no longer 115 120

locked in the casing is readily drawn away from under the wedge.

In the modified form of the invention as shown in Figs. 4 and 5 the prop 38 is provided with a single lug 39 on the front flange 40 in which is pivoted on a pin 41 a locking bar 42. To the lug 39 is also pivoted a draw-link 43 on a pivot 44, one arm of the link having a hook-like extension 45 adapted to engage the locking bar 42. The sides of the casing 46 are extended forward and shaped to provide hook-shaped lugs 47, one of which is turned upwards and the other downwards. In other respects, the parts of the prop are similar in construction to those in Figs. 1 to 3. Locking means to prevent accidental release of the prop may also be provided.

In use, the casing is shown in Figs. 4 and 5 locked on to the end of the prop. By connecting the draw chain to the end of the link 43 and after releasing any locking means, the first movement caused by pulling on the chain will be to raise that end of the link and by the engagement of the hook-like extension 45 with the locking bar 42, the latter is caused to rotate to the position shown in dotted lines in Fig. 5, or at least, so as to disengage from the lugs 47. The casing 46 is thus unlocked from the end of the prop and further pulling on the draw chain can act to draw the prop from under the wedge 48 and from out of the casing 46. The prop is fixed in the same manner as in fixing the prop shown in Figs. 1 to 3, by first locking the casing on to the prop and using the wedge 48 to tighten the prop in position.

As shown in Figs. 6 and 7 the prop 49 is provided with a single lug 50 on the front flange 51, in which lug is pivoted at 52 a link 53, the bifurcated ends of which are extended to provide hooks 54. A connecting link 55 is also provided on the link 53. The sides of the casing 56 are extended forward to provide two upwardly directed hooks 57 in which may be disposed a locking bar 58. In other respects the parts of the prop are similar in construction to those in Figs. 1 to 3. Locking means to prevent accidental release of the prop may also be provided.

In use, the casing is shown in Figs. 6 and 7 in position locked on the end of the prop. By connecting the draw chain to the link 55 and after releasing any locking means the first movement caused by pulling on the chain will be to pull down the link 53 so that its hooks 54 displace the locking bar 58 from the hooks 57. The casing 56 is thus unlocked from the end of the prop and further pulling on the draw chain can act to draw the prop from under the wedge 59 and out of the casing 56. The prop is fixed in the same manner as in fixing the prop shown in Figs. 1 to 3, by first locking the casing on to the prop and using the wedge 59 to tighten the prop in position.

As shown in the further modified example illustrated in Figs. 8 and 9, the prop 60 is provided with a casing 61 with a front 62 pivoted to the sides of the casing at 63 near its top edge. On the web of the prop are provided lugs 64 to which are pivoted S-shaped locking members 65 having operating arms 66 and the hooked ends of which are adapted to engage lugs 67 and 68 on the casing and casing front respectively. In other respects the parts of the prop are similar in construction to those in Figs. 1 to 3. Locking means to prevent accidental release of the prop may also be provided.

In use, the casing is shown in Figs. 8 and 9

in position locked on the end of the prop. By connecting the draw chain to the arms 66 and after releasing any locking means, the first movement caused by pulling on the chain will be to rotate the S-shaped locking members 65, so that their hooked ends are disengaged from the lugs 67 and 68. The casing 61 is thus unlocked from the end of the prop, further pulling on the draw chain acting to draw the prop from under the wedge 69 and out of the casing, the front 62 swinging up on its pivot to allow of such withdrawal of the prop. The prop is fixed in the same manner as in fixing the prop shown in Figs. 1 to 3, by first locking the casing on to the prop and using the wedge 69 to tighten the prop in position.

As shown in Figs. 10 and 11 the prop 70 is provided with a casing 71 formed of bent welded plate metal, at the top of which is provided a fixed head 72 so that the head and casing are combined as a single unit. The casing is formed with a rearwardly inclined rear side 73 so as to give an overhang for the head. In other respects the parts of the prop are similar in construction to those shown in Figs. 1 to 3. Locking means to prevent accidental release of the prop may also be provided as shown in Figs. 1 to 3.

In use the casing is shown in Figs. 10 and 11 locked on to the end of the prop. During withdrawal, it has been found occasionally that the prop shown in Figs. 1 to 3 may have a tendency to resist withdrawal when the prop is partly drawn. It is believed that this resistance is caused by a possible tilting action of the head and casing, owing to the fact that the prop has become slightly tilted and the rear edge of the top of the prop forms a fulcrum on which the head has a tendency to tilt forward. For this reason the overhang above mentioned is provided so that by the time the rear end of the top of the prop is capable of constituting a fulcrum, the pressure on the head from the roof is evenly distributed to prevent any tendency for the head to tilt forward with the inclination of the top end of the prop. The prop is fixed in the same manner as in fixing the prop shown in Figs. 1 to 3, the wedge 74 being used for tightening the prop in position.

As will be obvious, the invention is not limited to the details of the example above given, the principal features of the invention being the provision of a casing which enables the prop to be withdrawn from under the wedge.

The invention is applicable to other types of prop besides the H-section girder prop herein described.

What I claim is:—

1. A pit prop comprising a post, a casing or helmet loosely fitted on the upper end of the post and having an opening on one side large enough for the end of the post to pass through laterally, a wedge passing through the casing and over the upper end of the post with its smaller end nearer the said opening and locking means across the said opening for retaining the post within the casing.

2. A pit prop comprising a post, a casing or helmet loosely fitted on the upper end of the post and having an opening on one side large enough for the end of the post to pass through laterally, a wedge passing through the casing and over the upper end of the post with its smaller end nearer the said opening and locking means across the said opening for retaining the post

- within the casing, said locking means comprising a pivoted latch on the post and complementary locking means on the casing.
3. A pit prop comprising a post, a casing or helmet loosely fitted on the upper end of the post and having an opening on one side large enough for the end of the post to pass through laterally, a wedge passing through the casing and over the upper end of the post with its smaller end nearer the said opening and locking means across the said opening for retaining the post within the casing, said locking means including a pivoted member, having an arm which lies against the post when the said member is in the locked position and which is moved away from the post to unlock said locking means.
4. A pit prop comprising a post, a casing or helmet loosely fitted on the upper end of the post and having an opening on one side large enough for the end of the post to pass through laterally, a wedge passing through the casing and over the upper end of the post with its smaller end nearer the said opening and locking means across the said opening for retaining the post within the casing, said locking means including a pivoted member having an arm which lies against the post when the said member is in the locked position and which is moved away from the post to unlock said locking means, said arm being shaped for engagement by a prop withdrawing means.
5. A pit prop according to claim 2 wherein the locking means comprises a U-shaped member pivoted near its extremities to the post, extensions of said extremities projecting at right angles therefrom to extend along the sides of the casing and complementary locking formations on the said extensions and on the sides of the casing positioned so as to be engaged when the U-shaped member is lying against the post.
6. A pit prop according to claim 2 wherein the locking means comprises a U-shaped member pivoted near its extremities to the post, extensions of said extremities projecting at right angles therefrom to extend along the sides of the casing and complementary locking formations on the said extensions and on the sides of the casing positioned so as to be engaged when the U-shaped member is hanging beside the post from its pivot.
7. A pit prop according to claim 2 wherein the locking means comprises a U-shaped member pivoted near its extremities to the post, extensions of said extremities projecting at right angles therefrom to extend along the sides of the casing, complementary locking formations on the said extensions and on the sides of the casing positioned so as to be engaged when the U-shaped member is lying against the post and a chain link on said U-shaped member to receive the hook of a prop withdrawing machine.
8. A pit prop according to claim 2 wherein the locking means comprises a U-shaped member pivoted near its extremities to the post, extensions of said extremities projecting at right angles therefrom to extend along the sides of the casing, complementary locking formations on the said extensions and on the sides of the casing positioned so as to be engaged when the U-shaped member is lying against the post, a chain link on said U-shaped member to receive the hook of a prop withdrawing machine, and a locking pin adapted to be inserted into a hole in the side of the casing below one of the said extensions to prevent accidental unlocking move-
- ment of the U-shaped member and a relatively short chain connecting said locking pin to the chain link so that when the pin is in its hole the said link is held too close to the U-shaped member for the link to receive the hook of the prop withdrawing machine.
9. A pit prop comprising a post, a casing or helmet loosely fitted on the upper end of the post and having an opening on one side large enough for the end of the post to pass through laterally, a wedge passing through the casing and over the upper end of the post with its smaller end nearer the said opening and locking means across the said opening for retaining the post within the casing, the said casing or helmet having an overhang relative to the post away from the said opening.
10. A pit prop comprising a post, a casing or helmet loosely fitted on the upper end of the post and having an opening on one side large enough for the end of the post to pass through laterally, a wedge passing through the casing and over the upper end of the post with its smaller end nearer the said opening, locking means across the said opening for retaining the post within the casing, and means for slidably attaching the casing to the post and the wedge to the casing.
11. A pit prop comprising a post, a casing or helmet loosely fitted on the upper end of the post and having an opening on one side large enough for the end of the post to pass through laterally, a wedge passing through the casing and over the upper end of the post with its smaller end nearer the said opening, locking means across the said opening for retaining the post within the casing comprising normally fixed but removable projections on the casing entering closed-ended recesses in the post and wedge.
12. A pit prop comprising a post, a casing or helmet loosely fitted on the upper end of the post and having an opening on one side large enough for the end of the post to pass through laterally, a wedge passing through the casing and over the upper end of the post with its smaller end nearer the said opening and locking means across the said opening for retaining the post within the casing, said locking means comprising a latch bar pivoted centrally to one side of the post, hook-shaped extensions from the side of the casing, one facing upwardly and the other downwardly, with which the ends of the latch bar engage when positioned across the post and a lever pivoted beside the latch bar engaging the said latch bar to move it about its pivot from out of engagement with the said hook-shaped extensions.
13. A pit prop comprising a post, a casing or helmet loosely fitted on the upper end of the post and having an opening on one side large enough for the end of the post to pass through laterally, a wedge passing through the casing and over the upper end of the post with its smaller end nearer the said opening and locking means across the said opening for retaining the post within the casing, the said casing or helmet having a loose head-piece resting on the upper side of the wedge and slidably in the upper end of the casing.
14. A pit prop according to claim 13, further characterized by connecting means between the head-piece and the casing, to hold the head-piece captive to the casing whilst allowing of the sliding movement of the head-piece.
